D15-74.

OR D12,113 EX

Design No. 12,113, dated January 11, 1881.

UNITED STATES PATENT OFFICE.

JOHN E. DONOVAN, OF CINCINNATI, OHIO.

DESIGN FOR A LEG OF A SEWING-MACHINE TABLE.

SPECIFICATION forming part of Design No. 12,113, dated January 11, 1881.

Application filed November 26, 1880. Term of patent 7 years.

To all whom it may concern:

Be it known that I, JOHN E. DONOVAN, of Cincinnati, in the county of Hamilton and State of Ohio, have invented certain new and 5 useful Improvements in Design for Leg of Sewing-Machine Table; and I do hereby declare that the following is a full, clear, and exact description thereof, reference being had to the accompanying drawing, making a part 10 of this specification, in which is shown, in side elevation, my newly designed leg.

The essential feature of my design consists of the representation of a horseshoe, *a*, combined with and forming the central portion of 15 bars *b*, *c*, *d*, and *e*, which extend between and connect the upper and lower cross-bars, *f* and *g*, respectively, the whole forming the end support or leg of a sewing-machine table. Within 20 the horseshoe *a* are arranged centrally the letters and abbreviation "S. C. T. & Co.," in the form of a monogram, said letter "T" being at the upper end of a representation of the frog *h* of a horse's foot, while from the lower side, at the center of said frog, two representations 25 of the fore legs and feet of a horse, *i*, extend in diverging lines downward and outward, with the feet resting upon or against the inner edges of the bars *c* and *d*.

If desired, the fore legs and feet *i*, the frog 30 *h*, and the monogrammatic letters and abbreviation, or either of the same, may be omitted from the design.

Having thus fully set forth the nature and 35 merits of my invention, what I claim as new is—

1. The design for a table-leg for sewing-machines, consisting of the horseshoe *a*, combined centrally with the bars *b*, *c*, *d*, *e*, *f*, and *g*, substantially as shown and described.

2. The design for a table-leg for sewing-machines, consisting of the horseshoe *a*, combined centrally with the bars *b*, *c*, *d*, *e*, *f*, and *g*, and containing within its lines the letters and abbreviation "S. C. T. & Co.," arranged in the form of a monogram, substantially as shown 40 and described.

3. The design for a table-leg for sewing-machines, consisting of the horseshoe *a*, combined centrally with the bars *b*, *c*, *d*, *e*, *f*, and *g*, and containing the monogrammatic letters and abbreviation "S. C. T. & Co.," and the representation 50 of the frog *h* of a horse's foot, substantially as shown and described.

4. The design for a table-leg for sewing-machines, consisting of the horseshoe *a*, combined 55 centrally with the bars *b*, *c*, *d*, *e*, *f*, and *g*, and containing the monogrammatic letters and abbreviation "S. C. T. & Co.," the representation of the frog *h* of a horse's foot, and the representations of the fore legs and feet *i* of a horse, 60 substantially as shown and described.

In testimony that I claim the foregoing I have hereunto set my hand this 24th day of November, 1880.

JOHN E. DONOVAN.
